UNITED STATES PATENT OFFICE.

JOHN H. MACARTNEY, OF SAN FRANCISCO, CALIFORNIA.

FAN ATTACHMENT FOR ROCKING-CHAIRS.

SPECIFICATION forming part of Letters Patent No. 509,926, dated December 5, 1893.

Application filed March 27, 1893. Serial No. 467,833. (No model.)

To all whom it may concern:

Be it known that I, JOHN H. MACARTNEY, of San Francisco, in the county of San Francisco and State of California, have invented certain 5 new and useful Improvements in Fan Attachments for Rocking-Chairs; and I do hereby declare the following to be a full, clear, and exact description of the invention, such as will enable others skilled in the art to which it applies 10 pertains to make and use the same.

My invention relates to improvements in fan attachments for rocking-chairs, and its object is to provide a contrivance adapted to be attached to rocking-chairs, particularly 15 those of the base-rocker type, which contrivance may be capable of holding a fan, and be so constructed and arranged that in the ordinary act of rocking it may be operated to fan the occupant of the chair.

20 My invention more particularly resides in the novel combination, construction and arrangement of parts hereinafter fully described and set forth in the claims.

In the accompanying drawing I have represented 25 in perspective, a rocking chair with my invention attached.

A represents the base and B the rocking portion of a base rocking-chair.

Extending inwardly from and at right 30 angles to the base A is a rod C to the outer end of which is loosely secured by means of the nut D, the connecting rod E, the upper end of which is in turn loosely secured to the rocking shaft F, which carries the segment G 35 of a pinion and which turns in a bracket or bearing H, which is secured to upright portion I of the rocking-chair.

Extending upward through the bearing J is the flat bar or rod K on the upper and lower 40 portion of which are cut the teeth L which are adapted to mesh with the teeth in the segment G and pinion M, the latter being secured to a shaft N, which passes through bearings O secured to the back of the rocker B.

At the extremities of the shaft N are secured 45 by means of nuts P the fans Q, which extend forward over the seat of the chair.

I do not confine myself to any particular form of the fans N.

It will be readily seen from the drawing 50 that the fans are detachable, also that when it is desired the connecting rod E may be detached from the rod C thus throwing the device out of operation.

With this construction, the fans being properly adjusted, the occupant of the chair may by merely rocking in the ordinary manner impart an oscillating up-and-down motion to the fans.

The construction and arrangement of the 60 several parts of my invention being thus made known, the operation and the advantages of the same will, it is thought be readily understood.

Having thus fully described my invention, 65 what I claim, and desire to secure by Letters Patent, is—

In a rocking chair attachment, the combination with a swinging chair back of a segment pivotally secured to one side of the lower 70 portion thereof, an elongated curved vertically disposed rack bar having teeth near its opposite ends, an upper pinion in line with the segment, said rack bar engaging said pinion and segment, a transverse shaft on which 75 said pinion is mounted, fans on opposite ends of said shaft and means for oscillating said segment, substantially as described.

In testimony whereof I have signed this specification in the presence of two subscribing 80 witnesses.

JOHN H. MACARTNEY.
